MERCHANTISE DISPENSER

Lawrence C. Klemm and Walter E. King, Ashland, Ohio

Application February 9, 1948, Serial No. 7,117

3 Claims. (Cl. 312—71)

1

This invention relates to dispensing apparatus, and, more particularly, to apparatus for dispensing articles or packages of known size and weight.

The principal object of the invention is to provide a dispenser that displays the articles substantially in their entirety and facilitates removal of the articles by the consumer. This is accomplished by forming the dispensing apparatus so that the displayed article merely rests on a platform and is not wedged between the remaining articles, the arrangement being such that as soon as the displayed article is removed a new one takes its place.

Another object resides in utilization of gravity to operate the dispenser wherein the articles are stored below, and not above, the dispenser delivery point.

Another object resides in providing a gravity dispenser that is readily loaded in the same place that it is unloaded by the consumer.

A further object resides in facilitating adjustment of the apparatus for both the weight and height of the articles to be dispensed. These and other objects characteristic of the invention will be apparent to those skilled in the art as the following detailed description of a preferred embodiment proceeds.

In the drawings:

Fig. 1 is a vertical section through the apparatus when it is completely filled;

Fig. 2 is a similar view with one article removed;

Fig. 3 is a similar view with all articles removed except two;

Fig. 4 is a similar view with all articles removed except the last one; and

Fig. 5 is a transverse section taken on 5—5 of Fig. 4.

For convenience of illustration, I have disclosed a dispenser that contains seven articles when fully loaded, although it is understood that by lengthening the device any desired number of articles within reason may be accommodated.

The dispenser, in a preferred embodiment, includes a sheet metal housing H which has two vertical compartments, compartment 1 for the dispensed articles and compartment 2 for the balancing weights. The platform P is disposed in compartment 1 and rides vertically in a means of suitable carriage and track means. The track, or guide, is formed by an intermediate, generally C-shaped sheet metal No. 10, having terminal flanges 11 . The platform includes a carriage having vertical side members 13 joined by transverse cross pieces 14 and $14a$. Upper rollers 16

2

and lower rollers 17 are provided, and in order to reduce friction, I may offset the rollers so that the upper set engages flanges 11 , whereas the lower set engages the opposite wall of channel 10 , which reduces the friction forces involved. The flange 18 , integral with the platform, is attached by suitable means to the upper cross piece 14 , and a circular platform 19 supports the articles. I may provide a guiding ring 21 to center the lower article M_7 . Ears 22 may be struck from channel 10 to provide pivotal support for a guide pulley 23 . Depending flanges 24 may be attached to cap C to provide pivotal support for a second guide pulley 26 . Flexible tension means, such as cord, chain, wire or cable, 27 is rove over the pulleys and attached at one end to the carriage and at the other end to the lowermost weight W_6 .

In addition to weight W_6 , a plurality of counter-balance weights W_1 , W_2 , W_3 , W_4 , and W_5 , are provided, the uppermost weight, W_1 , being suspended by flexible means 28 such as chains or cables. As seen in Fig. 5, I may provide three members 28 , but it is to be understood that in Figs. 1 to 4, only two are shown in the interests of clarity. All but the lowest weights are apertured as at 30 to accommodate freely a master tension means 27 . Each of the weights underlying the uppermost weight W_1 is suspended from the weight above it by means of intermediate cables or tension means 28 and 29 . I may provide a platform 31 upon which the lower weight rests when the carriage is at its uppermost position. Stop means S may be provided to limit the free vertical travel of the uppermost weight W_1 .

It is to be noted that I may have one less weight than the number of articles to be dispensed. The lowermost weight W_6 is preferably equal to the weight of the carriage and platform assembly, plus a weight equivalent to more than 1 and less than 2 of the dispensed articles. For example, if canned goods are being dispensed (as illustrated in the drawings), the lower weight might equal the weight of the carriage plus the weight of 1½ cans of goods. The remaining weights are approximately equal to the weight of a corresponding dispensed article, and the distance D between the weights and between the upper weight and the stop S is equal to the height of the corresponding article to be dispensed, plus any additional allowance required for accommodation of the tension means 29 .

To understand the operation of the device, assume that the device is fully loaded as shown in Fig. 1, which in this form means that seven cans

are supported by platform P. The seven cans are partially counterbalanced by weights W₁ to W₆. Weights W₁ to W₅ total the weight of five cans and W₆ adds the weight of 1½ cans plus that of the carriage. In the remainder of the discussion, the weight of the carriage will be ignored because it is counterbalanced by an additional mass in the weight W₆.

Thus, in effect, we have seven cans on the platform and a weight corresponding to 6½ cans, supported by the flexible tension means 27. The result is that the platform will be urged to its lowermost position by the cans. As can M₇ is removed, an unbalance in favor of the weights results equivalent, in the example, to the weight of ½. Thus, the weights will begin to drop and raise the platform. As seen in Fig. 2, when the weights have dropped to the point where tension means 28 support the upper weight W₁, the platform has moved up the corresponding distance which is equal to the height of the can M₆. Now tension means 27 is relieved of the weight of W₁ and there remains suspended by tension means 27 a weight equivalent to 5½ cans, which is more than counterbalanced by the 6 cans on the platform. The platform can rise no higher under action of the weights because the unbalanced weight supported by tension means 27 is less than the weight of the six cans on the platform. Nor can the weight of the cans carry the platform lower because to do so it would have to lift the weight W₁ which would cause the total effect of the weights to exceed that of the remaining cans. Accordingly, the device will assume the position shown in Fig. 2 until another can is removed.

The process just described takes place as each can is removed, and, as shown in Fig. 3, when two cans remain, weights W₁, W₂, W₃, W₄, and W₅ are all suspended from the cap C. Weight W₆ is suspended from the tension means 27, but since it is approximately equal to the weight of 1½ cans it cannot lift two cans and so raise the platform from the position shown. Nor can the two cans cause the platform to drop from the position shown because to do so would require lifting of weight W₆, which, added to the weight of W₆, would be equivalent to 2½ cans.

Now, as seen in Fig. 4, as the next to the last can M₆ is removed, weight W₆ must only counterbalance the weight of the last can M₇. Since W₆ equals the weight of 1½ cans it will lift the remaining can and drop until it rests against the stop 31. Under these circumstances, the last can M₇ will be displayed ready for removal as seen in Fig. 4.

It will be understood from the following description that the weight W₆, which has been assumed to include that of 1½ cans, can conceivably be in the range of more than the weight of one to somewhat less than the weight of two cans, not considering the weight of the carriage. This provides a certain amount of leeway and permits accommodation to be made for static friction in the parts as well as the weight of tension means 27.

The mass of the various weights can be selected to equal that of a corresponding dispensed article. Either different weights may be used, or small auxiliary weights attached as is well known in the art. The length of the tension means 28 and 29 is adjusted for the corresponding height of the dispensed article. Any suitable means

may be provided for this adjustment within the scope of the knowledge of the skilled mechanic.

It can be seen that with my apparatus, the uppermost can is completely displayed and can be removed without hindrance from the remaining articles, as opposed to prior gravity dispensers wherein a large number of articles rest upon the lowermost article. The latter renders the articles difficult to remove, and they are only partially displayed. It can likewise be seen that our device is readily loaded from the point of discharge, and, since it extends downwardly from that point, the apparatus may be readily concealed in a cabinet shelf or the like.

Although I have illustrated a construction that embodies the invention, it is understood that numerous mechanical changes could be made by a skilled mechanic without departing from the mode of operation described. Accordingly, I contemplate that the appended claims, and not the aforesaid embodiment, be the measure of the scope of my invention.

What is claimed is:

1. Dispensing apparatus for discrete articles of predetermined height and weight comprising vertical framework means, platform means mounted for vertical reciprocation in said framework means, an upper weight and one or more underlying weights, means suspending each of said underlying weights from the weight above it, said suspending means being arranged to provide a predetermined free vertical reciprocation between each underlying weight and the weight above it, means suspending said upper weight from said framework arranged to provide a predetermined free vertical reciprocation of said weight, guide means carried by said framework above said upper weight, and flexible tension means running over said guide and attached at one end to the lowest of said weights and at the other end to said platform means, the weights above said lower weight being slidable relative to said tension means, all of said weights except the lower weight being equal to one another and to the weight of an article to be dispensed, the lower weight equaling the total weight of the carriage, an upper weight, and a fraction of an upper weight less than one.

2. Dispensing apparatus for discrete articles of predetermined height and weight comprising vertical framework means, platform means mounted for vertical reciprocation in said framework means, an upper weight and one or more underlying weights, flexible tension means suspending each of said underlying weights from the weight above it and suspending said upper weight from said framework, guide means carried by said framework above said upper weight, and flexible tension means running over said guide and attached at one end to the lowest of said weights and at the other end to said platform means the weights above said lower weight being equal to the weight of an article to be dispensed and being slidable relative to said tension means.

3. Dispensing apparatus for discrete articles of predetermined height and weight comprising a framework including a pair of parallel vertical generally tubular elements, a track parallel to said tubular elements, platform means in one of said elements, said platform means including a carriage reciprocable in said track, an upper weight and one or more underlying weights disposed in the other of said tubular elements,

flexible tension means suspending each of said underlying weights from the weight above it and suspending said upper weight from said framework, guide means carried by said framework above said upper weight, and flexible tension means running over said guide means and attached at one end to the lowest of said weights and at the other end to said platform means.
